DOOR CATCH.

Application filed April 29, 1927. Serial No. 187,605.

This invention relates to improvements for latching and holding doors.

The primary object of this invention is the provision of a simple type of door catch which is adapted for use in connection with casing and door portions of buildings, whereby to enable the door to latch in convenient manner whenever it is closed.

A further and important object of this invention is the provision of a latch structure for doors embodying means by which the latch structure may be dogged to prevent unauthorized persons from outside the building structure from operating the same.

15 A further object of this invention is the provision of an improved latch structure which may be used in connection with swinging or sliding types of doors, and which is reversible for use at either side of the door, 20 depending upon the side to which it is to be attached.

Other objects and advantages of this invention will be apparent during the course of the following detailed description.

25 In the accompanying drawing, forming a part of this specification, and wherein similar reference characters designate corresponding parts throughout the several views,

Figure 1 is a view taken sectionally through 30 a portion of a door structure, and showing the improved latch as it is connected to a jamb or casing portion of the door structure, this view being taken substantially on the line 1—1 of Figure 2.

35 Figure 2 is a fragmentary view of a front portion of a door structure, showing a novel type of keeper which may be used in connection therewith to receive the hook portion of the latch.

40 Figures 3 and 4 are side elevations of the improved latch structure, showing a cover portion thereof removed to expose working details of the hook when in latched and unlatched positions.

45 Figures 5 and 6 are cross sectional views taken substantially on their respective lines in Figure 3 of the drawing.

50 Figure 7 is a view, partly in cross section, showing the manner in which the improved door catch may be used in connection with sliding door structures.

55 In the drawing, wherein for the purpose of illustration is shown only a preferred embodiment of this invention the letter A may generally designate the improved door catch,

which embodies a casing structure B; movable bolt C; and keeper D. The improved door catch A as used in connection with two types of doors preferably has the casing structure B secured to the jamb portion F adjacent the swinging door G. In connection with sliding doors H such as illustrated in Figure 7 the casing B is secured to the door, and a novel type of keeper structure K is used in the casing L adjacent the door H.

60 Referring to the details of the casing structure B, the same preferably is of two-part construction, including parts 15 and 16, of complementary formation, which are substantially rectangular in outline and which provide the upper and lower rib portions 17 and 18 along the upper and lower marginal edges of each of the same, to provide a pocket 19 adapted to pivotally receive the bolt or hook C therein when the casing portions 15 65 and 16 are secured together.

65 Referring now to the structure of the hook C, the same may be of any material, preferably iron, and includes a body portion 25 which at the lower corner thereof has an opening 26 preferably a slot, which receives therethrough a pin 27 which is carried transversely across the compartment 19 by means of the casing portions 15 and 16, so that the bolt or hook C is pivoted intermediate its ends. The body portion 25 surrounding the aperture or opening 26 is somewhat reduced, and the side surfaces of this reduced portion rest in abutting relation upon substantially 70

75 disc-shaped portions 30 formed on the insides of the casing portions 15 and 16, extending inwardly of the compartment 19 thereof, as is illustrated in the drawing, so that the hook C at the place of its pivotal connection is mounted in sliding contact with the relatively small 80 projecting portions 30, and so that the side surfaces of the body portion 25 otherwise do not contact the inside surfaces of the casing portions 15 and 16, thus facilitating pivotal 85

90 movement of the hook C. At the forward end the hook C provides a reduced head 35, which at its juncture with the body portion 25, on each side of the hook C provides shoulders 36, as illustrated in Figure 5 of the drawing. In position within the casing B the bolt or hook C at its reduced head portion 35 95 extends through the front opening 40 of the casing, so that the shoulders 36 may have an abutting action against rib portions 42 which are provided in projecting relation toward 100

105

110

the shoulders 36 at the front edges of the casing portions 15 and 16, and as is illustrated in Figure 5 of the drawings. The shoulders 36 abut against the ribs 42 when there is any 5 tendency to pull the hook C from the casing, incident to attempting to open the door, and thus reinforce the position of the hook C, relieving some of the strain which would otherwise occur on the pivot pin 27. The head 35 10 includes a lower recess 46, adapted to receive suitable securing mechanism with the keepers D or K, as will be subsequently described, and the head portion 35 has the upper and lower edges 47 and 48 thereof tapered in converging 15 relation toward the front edge 49 thereof, to facilitate operation of the hook C, as is obvious. Adjacent the front surface 49 the head 35 is preferably provided with a transverse opening 50 adapted to receive there- 20 through a pad lock or similar locking arrangement in connection with swinging types of doors, and this feature will be subsequently described.

The hook C has a rearwardly extending 25 handle 51, which may be square in cross section, and extends rearwardly from the body portion 25 at the upper surface thereof flush with the top edge of the body portion 25, and which has the rear end thereof extending 30 through an opening 56 which occurs at the rear end of the casing B, so that a person may engage the rear end of the handle 51 to pivotally move the hook or bolt C. The handle 51 has a depending lug 58 which provides a 35 surface 59 in right angled relation with respect to the run of the handle 51, which is adapted to receive in engaging relation there-against the upper end of a substantially L-shaped pawl or detent 60 which is pivotally 40 connected, as at 61, to the casing portions 15 and 16 in the rear opening 56 thereof. The detent 60 may be swung so that a laterally ex- 45 tends leg portion 62 thereof engages against a shoulder 63 of the casing, and in which instance the leg portion 64 thereof is in depending relation exteriorly of the casing where the same may be easily reached by an operator. In this position the hook C is 50 free to swing for unlatching the door. In the other position of the pawl or detent 60, and which is illustrated in Figure 3 of the drawing, the leg portion 64 is substantially vertically disposed in resting relation at its upper end against the hook lug 58, and in 55 which position it is retained by gravity to maintain the bolt C in a locked relation with respect to its keeper structure. In this position the leg portion 62 extends slightly outwardly from the casing where the same may be readily engaged by the finger of a person to facilitate outward swinging of the detent.

In connection with the mounting of the casing B upon a jamb, screws 65 may be employed for securing the sections 15 and 16 together, these screws having their heads

countersunk in the casing sections 15 and 16, and other screws 66 may be used for not only connecting the sections 15 and 16 together, but which may extend into the jamb portion F, as is illustrated in Figure 6 of the drawing, 70 in order to mount the casing portion B so that the hook head 35 projects from the forward edge of the jamb F, where the same may readily enter the keeper D.

Referring to the keeper D, the same is of 75 novel construction, preferably formed of sheet material, and including an attaching portion 70 which may be of triangular shape, adapted for attachment to the front surface of the door G by countersunk screws 72, and 80 which attaching portion has a handle 74 pivotally mounted thereon. This attaching portion 70 is apertured, at 75, adapted to be positioned in alignment with a slot 77 similarly provided through the door structure G, and 85 through slots 77 and 75 the head of the hook C may project. The keeper structure D also includes a flange portion 79 at right angles to the attaching portion 70, and adapted to overlie the edge 80 of the door G, and which flange 90 95 is provided with upper and lower openings 81 and 82 therein. The lowermost opening 82 receives a pin 83 therethrough, the shank portion of which is driven into the material of the door G, as is illustrated in dotted lines in Figure 2, so that this portion extends transversely across the opening 77 and provides a keeper pin or element which may be received within the recess 46 of the latch hook C.

In operation with the swinging type of 100 door G, the casing B and hook C is mounted as above mentioned upon the jamb F, and the keeper structure D mounted upon the door G. When the door G swings closed the keeper pin 28 will engage the tapered surface 48 of the hook head 35, and will elevate the forward end of said hook C until hook C will fall by gravity to receive the keeper pin 83 therein. In this position the apertured end of the hook head 35 projects outwardly from the keeper 105 attaching portion 70, and through the aperture 50 a padlock or similar arrangement may be placed to positively lock the door structure in a closed relation with respect to the latch. The locking arrangement may also be effected 110 by means of the detent 60, as above described. 115

Referring to the use of the improved latching device A upon the sliding type of door, a pocket 90 is provided on the inside of the door, within which the casing B of the latch device A fits, so that the outside of the casing is flush with the inside surface of the door H, and so that the end edge 91 of the casing B is also preferably flush with the front edge 92 of the door H. In this relation of parts 120 a recess 94 will have to be provided inwardly of the inside surface of the door, to permit free pivotal movement of the detent 60 into holding and release positions. The hook head 35 projects outwardly from the forward 125 edge of the door H, and the keeper 70 is 130

- edge of the door, and to facilitate operation of the latch device A from the outside of the door it is preferred to provide a relatively small aperture 96 through the door, so that 5 a person may insert a finger for operating the rearwardly projecting handle 51 of the hook C, although this aperture is not sufficiently large to permit operation of the detent 60.
- 10 A special type of keeper K is employed in connection with the sliding door device A, and this preferably comprises a box shaped member 97, providing a compartment 98 therein, laterally through which a keeper pin 99 is supported, preferably adjacent the lower part and forward face thereof, over which the hook head 35 may engage in accordance with the above described structure. Upper and lower attaching flanges 100 and 101 are 20 provided integral with the box 97, which may be countersunk in the edge of the jamb L, and countersunk screws 102 are disposed through these flanges into the jamb L. The pocket 98 is of course open at the edge of the jamb so that the hook head 35 may readily enter the same, and the keeper pin 99 may ride along the tapered surface 48 of the hook head 35 to elevate the same and permit locking of the door to the jamb L.
- 25 30 Various changes in the shape, size, and arrangement of parts may be made to the form of invention herein shown and described, without departing from the spirit of this invention or the scope of the claims.
- 35 I claim:
1. In a latch structure of the class described a case providing a compartment therein and an opening forwardly therethrough with ribs projecting laterally and inwardly 40 of the compartment adjacent said forward opening, and a bolt pivoted in the compartment of said case including shoulders adapted for cooperation against the ribs of said case and a reduced forward head portion provided 45 with a recess therein which projects through said forward opening between the ribs.
  2. In a latch structure of the class described a case providing a compartment therein, a hook including a body portion having a forwardly extending reduced head provided 50 with a recess therein and a rearwardly extending reduced handle, means pivotally mount- ing the hook within the case so that the forward end head and rear handle portion thereof extend respectively through the forward and rear ends of said case, said body portion of the hook being formed to engage the case when a pull is exerted on the head of the hook to draw it outwardly of the case. 55
3. In a latch structure of the class described the combination of a casing portion including a pair of sections provided with upper and lower inwardly extending flanges thereon, means connecting the casing portions so that the flanges are in abutment to provide a compartment between said sections, said casing sections providing inwardly projecting lugs with a pin supported therebetween, a bolt pivotally mounted intermediate its ends upon said pin so that the same is in engagement with said inwardly projecting lugs whereby to support the bolt in stable relation within said compartment to prevent lateral sway thereof. 60
4. In a latch structure of the class described a casing including a compartment, and a hook pivoted intermediate its ends in said compartment, said hook including a forward reduced head portion having a recess upwardly therein and converging upper and lower surfaces, said hook and casing including cooperating shoulders adapted to come into engagement with each other when force is applied to the hook tending to withdraw the same from the casing. 65
5. In a latch structure a casing having a compartment therein, a hook member pivoted between its ends in said compartment, the casing at opposite ends thereof having openings therethrough to the compartment, said hook member having a hook head on one end thereof extending through one opening at an end of the casing, and having a handle at its opposite end extending through the other end opening of the casing, an L-shaped detent pivoted on the casing having a portion adapted to engage the hook entirely within the compartment to hold the hook in a locking position, said detent when so positioned having a short extension projecting from the casing for finger engagement to release the detent from its locking relation with the hook. 70
